UNITED STATES PATENT OFFICE.

HENRY BLACKMAN, OF NEW YORK, N. Y.

APPARATUS FOR DISINTEGRATING FIBERS AND RECOVERING SULFUROUS GASES EMPLOYED THEREIN.

SPECIFICATION forming part of Letters Patent No. 530,634, dated December 11, 1894.

Original application filed October 21, 1889, Serial No. 327,615. Divided and this application filed June 9, 1890. Serial No. 354,760. (No model.)

To all whom it may concern:

Be it known that I, HENRY BLACKMAN, a citizen of the United States, residing in New York city, in the county and State of New York, have invented certain new and useful Improvements in Apparatus for Disintegrating Fibers and Recovering Sulfurous Gases Employed Therein, of which the following is a specification.

10 This application is a division of my application for patent for process and apparatus for making paper pulp, filed October 21, 1889, Serial No. 327,615.

This invention relates to what is known as 15 the "sulphurous" or "sulphite process" of disintegrating fibers for the manufacture of paper pulp. It involves in part the use of what is known as the "vacuum process" of disintegrating fibers, described and claimed 20 in my Patent No. 369,836, dated September 13, 1887.

According to what is known as the "sulphurous" or "sulphite process" of making paper pulp, the wood, straw, or other fibrous 25 matter is exposed in a digester under considerable pressure and at a high temperature, to the action of a solution of sulphurous acid, or preferably of a sulphite of soda, potash, lime, or other alkali or base. The boiling is con- 30 tinued for several hours, during which time by the action of the sulphurous or sulphite solution, the gummy or resinous matters, or other cementing substances that bind the fibers together, are decomposed or dissolved, 35 thereby freeing the pure cellulose which constitutes the essential portion of the fibers, so that at the conclusion of the digesting operation the fibrous matter is discharged as an impure pulp requiring only washing and 40 beating to fit it for use. The digester employed usually consists of a steel shell of great strength to withstand the heavy pressure, and lined with lead to resist the corrosive action of the acid solution. The solution usually 45 and preferably employed consists of a mono- sulphite or bisulphite of lime with an excess of sulphurous acid. This solution is prepared in various ways, one method being to introduce lime water into the digester and then 50 force sulphurous acid gas into the digester while agitating its contents, so that the solu-

tion is prepared in the digester itself. Another method is to prepare the solution in what is called a lime tower, consisting of a tower or stack filled with pieces of limestone, 55 or containing trays of lime, water being caused to trickle down through the lime or limestone, while sulphurous acid gas is admitted at the bottom of the tower from a retort in which sulphur is burned, or in which pyrites are 60 roasted. The ascending gas combines with the descending lime-impregnated water, forming a solution of sulphite of lime which is carried off from the bottom of the tower and is eventually pumped into the digester. In 65 this process it has usually been necessary or advisable to force an additional proportion of gas into the digester.

The acid or sulphite process of disintegrating fibers is subject to certain disadvantages, 70 among which may be mentioned the frequent discoloration of the fiber, due it is believed, to the presence of a residue of sulphur gases in the pulp, which upon its exposure to the atmosphere gives rise to chemical reactions 75 by which the color of the pulp is impaired. The sulphur gases also escape into the atmosphere upon the discharge of the pulp from the digesters, thereby giving rise to intensely disagreeable odors about the mill and constituting it a nuisance to the neighborhood. The discharge of the spent liquors into 80 streams or rivers results in poisoning their waters and gives rise to unhealthy odors. The prevention of these difficulties, as well 85 as the attainment of a greater economy in the working of the sulphite process, is an important object of my present invention.

In accordance with my present invention I provide one or more digesters such as are used 90 in the well known sulphite process, and a vacuum chamber or tank to which the digester is connected so that its contents may be blown off into the vacuum chamber, which has a capacity sufficient to receive the entire charge 95 from one digester. Since this vacuum chamber is normally closed at its bottom and is so constructed as to retain the entire charge of fibrous material discharged into it from the digester, which retaining feature is one of its 100 herein characteristic and important features, it may be appropriately designated a "vac-

uum retaining chamber" and this designation is hereinafter adopted. I also provide a pump for maintaining a vacuum in this chamber, and between the pump and vacuum retaining chamber I provide a vapor separator and condenser. I also provide a closed tank having agitating devices called the "sulphite mixer," and another closed tank, preferably with agitating devices, called the "recovery tank." These several tanks or vessels are connected together through suitable pipes suitably provided with valves for regulating the flow of gases or liquids therethrough and connected with pumps for circulating the gases or liquids.

In using this apparatus I proceed preferably as follows:—The chipped wood or other fibrous matter is digested in the usual or any suitable way in a solution of sulphite or bi-
sulphite of lime or other base, in a suitable digester, and under the necessary heat and pressure. At the end of the period of digestion, and preferably also one or more times during the digesting, the fibrous matter is "disrupted" by being blown off from the digester into a vacuum, in accordance with my vacuum process of disintegration described in my aforesaid patent. This disruption is accomplished by blowing off the fibrous matter and liquor from the digester into the vacuum retaining chamber under a considerable pressure in the digester, and at a high temperature, while in the vacuum retaining chamber a vacuum or rarefaction is maintained by the operation of the vacuum pump. The fibrous matter enters the vacuum retaining chamber through a contracted nozzle or orifice, on escaping from which into the vacuum the liquid in the cells of the fibrous matter being suddenly relieved of pressure is vaporized or converted into steam which tears the fibers asunder, or disrupts them. The steam, vapor and solvent gas pass out at the top of the vacuum retaining chamber and are carried through the condenser in which the steam is condensed and passed thence to the pump. The fibrous matter falls to the bottom of the vacuum retaining chamber together with the portion of the liquor which is not vaporized. During the blowing off the disengaged gas is pumped from the vacuum pump back into the top of the digester to assist in maintaining the pressure therein. At each intermediate blowing off, when the entire contents of the digester have been blown off into the vacuum retaining chamber they are returned again to the digester either by pumping them back or by opening valves and turning a pressure of steam into the vacuum retaining chamber sufficient to force them to flow through the communicating pipe from the vacuum retaining chamber into the digester. This return or transfer of the fibrous matter and liquor may be assisted by forming a vacuum in the digester by connecting it with the vacuum pump. This disruption of the fibrous matter by

blowing it off into the vacuum retaining chamber and the subsequent return of the fibrous matter to the digester should be practiced several times during the period of digestion. At one of the disruptive operations, and preferably after the digestion has been continued about eight or ten hours, the liquor or sulphite solution should be changed. At this time the gases drawn from the vacuum retaining chamber during the blowing off are forced from the vacuum pump into the "sulphite mixer," where they are utilized for the production or enrichment of the sulphite solution therein. The fibrous matter having all been discharged into the vacuum retaining chamber, the pressure in the latter is restored to that of the atmosphere, or to above atmospheric pressure, and the spent liquor is drained off from the fibrous matter, being carried into the "recovery tank." Fresh liquor or sulphite solution is then introduced into the vacuum retaining chamber, and the fibrous matter and fresh liquor are pumped or blown back from the vacuum retaining chamber into the digester, whereupon the digesting process is resumed. When the digestion is completed the pulp is subjected to a final disruptive blowing off into the vacuum retaining chamber. During this blowing off it is preferable to pump the pulp and liquor back from the vacuum retaining chamber into the digester as fast as it enters, so that it may again be blown out and kept in circulation until it has been blown through the contracted nozzle into the vacuum retaining chamber as many times as may be desired to complete the separation of the fibers. When the entire mass has thus been circulated two or more times, the pulp outlet from the vacuum retaining chamber is closed and all the pulp from the digester is blown into the vacuum retaining chamber. During the entire final blowing off the sulphurous gas is pumped into the sulphite mixer where it is utilized for the production or enrichment of the sulphite solution therein. When the entire charge of pulp has been accumulated in the vacuum retaining chamber the vacuum is discontinued and the spent liquor is drained off from the pulp into the recovery tank. The pulp is then still impregnated to a considerable extent with sulphurous acid gas, for the removal of which the pulp is heated while under vacuum. This is accomplished by injecting steam into the bottom of the vacuum retaining chamber so that it passes upward through the mass of pulp, the gas thus liberated and the steam being drawn off by the vacuum. Thus nearly every trace of sulphurous gas is eliminated from the pulp. Hot water is then introduced into the top of the vacuum retaining chamber and the accumulated pulp is washed out to the pump which pumps it to the usual "wash tanks" where it is washed in the usual manner and is run into the usual "clean pulp chest." It may then be used in any known

way for paper manufacture. In the "sulphite mixer" the sulphite solution is prepared. The sulphurous gases thus drawn out by the vacuum pump during the different stages of the operation whenever they are not forced back into the digester are forced into this sulphite mixer. Lime water is also introduced to the mixer in suitable proportions and the gas and liquor are thoroughly commingled by the action of the revolving agitator in the mixer. In case a jet condenser is used for condensing the steam or vapor drawn from the vacuum retaining chamber, it is preferably supplied with cold lime water which combines with some of the sulphurous gas and which is then pumped into the sulphite mixer. Additional lime water is introduced directly into the mixer whenever necessary.

In the recovery tank the spent liquor is heated under vacuum and the sulphurous gas thus driven off is pumped to the sulphite mixer. This heating of the liquor is preferably accomplished by injecting steam into it at the bottom of the tank. The remaining liquor may then be treated for the recovery of its tannic acid and other valuable constituents, after which the residue of liquor will be run off to the sewer.

The present improved apparatus is illustrated in the accompanying drawings, wherein—

Figure 1 is a general view of the apparatus on a small scale chiefly in elevation, but partly in vertical section. Fig. 2 is a vertical section on a larger scale of the digester, vacuum retaining chamber, condenser, and their communicating pipes. Fig. 3 is a vertical section on the same scale as Fig. 2, of a tank having an agitator within it, which may be either the sulphite mixer or the recovery tank. Fig. 4 is a horizontal section of part of Fig. 1, cut on the plane of the line 4—4 therein.

Referring to the drawings, A designates the digester; B, the vacuum retaining chamber; C, the condenser; D, the vacuum pump; E, the sulphite mixer; F, the recovery tank; G, one of the wash-tanks and H the boiling tank. I, J, K and L are pumps which may be centrifugal pumps.

The digester A may be of any known construction, such, for example, as either of those shown in my Patents Nos. 369,836 and 369,834 of September 13, 1887. In the construction shown it consists of a steel outer shell with an inner lining of lead, as is common in working under the acid or sulphite processes, with a large opening a at its top through which to introduce the fibrous matter, and an outlet a' at its bottom from which leads a pipe b connecting with a pipe b' extending to the vacuum retaining chamber B, and there terminating in a contracted nozzle or discharge orifice c. In the bottom of the digester is fitted a conical screen or false bottom a² in the space beneath which is preferably a steam-coil or jacket d, the admission of steam to

which from the steam-pipe S is controlled by a valve 5. From the space beneath the screen a², a pipe e leads to the pump I, and a pipe e' leads from this pump to the upper part of the digester, which it enters. Thus by operating this pump the liquor may be drawn down through the mass of fiber which rests on the screen a² and returned into the top of the digester, thus instituting a circulation of the liquor through the fibrous matter. The outlet a' is closed by a valve 6 in the discharge pipe b. Steam from the pipe S is admitted into the top of the digester through a valve 7.

If the tank H is not used the inlet opening a at the top of the digester is closed by a man-hole plate, as shown in Fig. 2. When the tank H is employed, however, it is arranged preferably directly over the digester and communicates therewith through an outlet-pipe f entering the opening a and closed by a valve 8. The tank H has a perforated screen or false bottom f' in the space beneath which is a steam coil f² into which steam is admitted through the valve 9 in order to supply heat for boiling the fibrous matter in the tank.

The vacuum retaining chamber B is the same in its disruptive principle of operation as the vacuum retaining chambers shown in my said Patents Nos. 369,836 and 369,834. Instead, however, of being a comparatively shallow box or chamber partially divided by a pendent partition or target and with an always open outlet at the bottom, it is constructed as a large upright vessel, preferably cylindrical, normally closed at its bottom and having a capacity sufficient to receive and maintain in its lower portion the entire contents of the digester A. The nozzle c enters it at one side near its top and directs the stream of fibrous matter against the target g, which is arranged to project down from the top of the chamber. This target has the same function as the target F' in my Patent No. 369,836. In the bottom of the chamber is a conical screen or false bottom g' opening downward to the outlet-opening g' from which a pipe h governed by a valve 10 leads to the pump L. This pump discharges into a pipe h' from which there are two branches, one of which, h², extends upward and enters the top of the digester A, being governed by a valve 11. The other branch, h³, leads to the wash-tank G, into which it discharges, being governed by a valve 12.

From the top of the vacuum retaining chamber B a vapor-pipe i extends upwardly, being provided with a valve 13, and enters a vapor separator C' which consists of a box or chamber having a pendent target or partition i' in its upper part to deflect downwardly the stream of vapors flowing through the chamber on their way to the outlet-pipe a². This outlet pipe leads into the top of the condenser C, which may be of any construction common for condensers, and either a surface or a jet condenser. The condenser shown is a jet condenser, receiving cold water, preferably

lime-water, from the pipe W which enters the upper part of the condenser, and is perforated to throw jets of water thereinto in contact with the steam and vapors, the water thus introduced being controlled by a valve 15. The injected water and the water of condensation fall to the bottom of the condenser and flow off by a pipe j leading to the pump J, while the uncondensed gas and vapors, consisting chiefly of sulphurous gas and steam, flow out of the side of a pipe k which leads down and communicates through the two-way valve 14 with the suction-pipe k' of the vacuum pump D. The uncondensed steam or vapor is condensed in this pipe k by cold water showered thereinto from a perforated pipe k², fed by a branch from the pipe W and controlled by a valve 16. The vapor which is separated in the chamber C' flows down a pipe i³, and is discharged either through a pipe i⁴ into the condenser C, or through a pipe i⁵ back into the vacuum retaining chamber B, its flow being determined by a two-way cock 17.

25 The vacuum in the chamber B is maintained by the operation of the pump D, which draws the gases or vapors out through the pipe i, separator C', condenser C, and pipe k, the valve 14 being in the position shown in Fig. 2. In order that the same pump may also serve for drawing the sulphur gas from the top of the digester A, a pipe l is provided leading from the top of the digester and communicating with the pump, preferably by joining the pipe i above its valve 13, so that by closing this valve and opening a valve 18 in the pipe l the gases or vapors may be drawn through this pipe and through the separator C', condenser C and pipe k to the pump. The gases drawn off by the pump are discharged through a pipe m in either of three different directions, namely: first, through a branch pipe m' governed by a valve 19 into the sulphite mixer E; second, through a branch pipe n into a long main pipe p which extends from the pump K to a pipe p' communicating with the digester or digesters, as will be presently described, the flow through the pipe n being governed by a valve 20; third, in case a lime tower is used the gas may be discharged through a branch pipe m² governed by a valve 21 and leading to the tower.

50 The liquid which descends from the condenser C and which will usually be rich in sulphurous gas, is forced by the pump J through the pipe j' into the sulphite mixer E, this pipe being provided with a valve 22.

55 The sulphite mixer in addition to the inlet pipes m' and j' for gas and liquid is provided, as shown in Fig. 1, with an inlet pipe W' for admitting lime water, being governed by a valve 23, and with a pipe M' for admitting sulphurous gas from the retort or furnace in which this gas is produced, its admission being governed by a valve 24. In addition, the sulphite mixer is provided with an outlet pipe o governed by a valve 25, and leading

60 to the pump K, by which the sulphite liquor or solution prepared in the mixer E is discharged into the digester, or wherever else it is required.

65 The sulphite mixer, which is a closed tank of considerable strength, is provided preferably with agitating devices, as shown in Fig. 3. In this preferred construction the agitator consists of a vertical shaft t carrying lateral arms t' to which are fixed stirring-arms or cross-pieces t² t², which as they revolve alternate with fixed arms t³ t³, mounted on a cross-bar t⁴, which is supported from the walls 70 of the tank. The shaft t is stepped in a cup-bearing at its lower end, and passed out through the stuffing-box in the top of the tank, its upper end being driven by any suitable gearing.

75 The liquor from the sulphite mixer is pumped by the pump K through the pipe p, and either through the pipe q which enters the upper part of the vacuum retaining chamber B, the flow into this pipe being governed by a two-way valve 26, or it is pumped through the entire length of the pipe p into the pipe p' and thence into the digester either through a pipe r or a pipe s. The pipe r enters the bottom of the digester beneath the screen a², and 80 is controlled by a valve 27. The pipe s extends to the top of the digester, the flow through it being controlled by a valve 28. The pipe p is furnished with a valve 29 between the pump K and branch pipe n in order to prevent any back flow from the pump D through the pipes n and p toward the pump K. Warm or hot water is supplied by a pipe W², which has two branches, one leading to the boiling tank H and controlled by a valve 30, and the 85 other leading to the top of the vacuum retaining chamber B and controlled by a valve 31.

90 The steam pipe S in addition to branches communicating through the valves 9 and 5 with the tank H and digester A respectively, has also a branch pipe s' leading to the top of the vacuum retaining chamber B, and controlled by a valve 32, a branch s² leading to the bottom of the vacuum retaining chamber beneath the screen g' therein and controlled 95 by a valve 33 and a branch s³ leading to the outlet a' from the digester and controlled by a valve 34.

95 The recovery tank F is a closed vessel of suitable strength and lined with lead to resist 100 corrosion, and preferably fitted with the same agitating devices as the sulphite mixer E, as shown in Fig. 3. The spent liquor from which the sulphur gas is to be recovered is discharged into this tank through a pipe u leading from the bottom of the vacuum retaining chamber B beneath the screen g' and entering the recovery tank, preferably at the bottom. It is controlled by a valve 35. From the top of the tank F a pipe v extends to the 105 three-way valve 14 by which it may be put into connection with the suction-pipe k' of the vacuum pump in order that this pump may draw the sulphurous gas from the tank F.

The liquor is heated by steam admitted through a pipe S' controlled by a valve 36, either by admitting the steam directly into the liquor, or by the use of a steam-coil or jacket. After the sulphurous gas has been recovered by the action of the heat and vacuum, the liquor may be treated for the recovery of tannic acid or any other valuable constituents that it may contain, or it may be treated to deodorize or otherwise purify it. For this purpose any chemical agents may be introduced through a funnel inlet of any usual construction. Finally the spent liquor is discharged through the pipe w leading to the sewer or elsewhere, and governed by valve 37.

The pump D may draw the sulphurous gas either through the pipe k, or from the tank F through the pipe v, or from the retort in which this gas is generated through a pipe M, which latter pipe communicates with its suction chamber, being controlled by a valve 38.

The wash-tank G is of any usual construction, and requires no description.

Preferably two or more digesters A are employed, since with a single digester the vacuum retaining chamber B, pump D, recovery tank F, &c., would be idle the greater part of the time.

In Fig. 4 I have shown in horizontal section a battery of three digesters, A A A, all connected to the one vacuum retaining chamber B. The outlet pipes b of the three digesters all communicate with a single cross-pipe b', through which they are put into connection with the pipe b' which extends up to the nozzle c. The single discharge pipe from the pump L enters a transverse pipe h', from which three vertical pipes h² ascend and lead to the respective digesters. The single pipe p communicates with a transverse pipe p' extending under the three digesters, and from which three vertical pipes r r ascend and enter the bottoms of the digesters, while three pipes s s branch laterally from the pipe p' and extend to the tops of the respective digesters.

The several valves numbered from 5 to 38 may be of any suitable constructions, some of these being gate-valves, others being globe-valves, and others being two-way cocks.

The general operation of the apparatus will be well understood from the description which I have given of the mode of operation. I will, however, describe some of the operations of the apparatus which may not be apparent from such description. After the fibrous matter has been placed in the digester, the solution or liquor is introduced into the digester from the sulphite mixer by the pump K, flowing through the pipes o p, and either r or s, according as it is desired to introduce it at the bottom or at the top of the digester. It will usually be introduced at the top, in which case the valves 25, 29 and 28 will be opened. In order to blow off the fibrous matter into the vacuum retaining chamber to disrupt it, the valve 13 is opened, the two-way

cock 14 is set to the position shown, and the pump D is started and operated until a sufficient vacuum is produced in the chamber 70 B.

A sufficient pressure being maintained in the digester A, the valve 6 is opened, whereupon by reason of the pressure behind it, and the suction in advance, the fibrous mass is forced out and flows in a continuous stream 75 through the nozzle c into the vacuum chamber. The fibrous matter falls to the bottom of the chamber and may be immediately and continuously pumped back through the pipes h, h' and h² by opening the valves 10 80 and 11 and operating the pump L, whereby the fibrous matter will be circulated between the digester and vacuum chamber until it has passed through the nozzle as many times as may be desired; or the fibrous matter may, 85 by keeping the valve 10 closed, be permitted to accumulate in the vacuum retaining chamber. At each intermediate blowing off or disruptive operation, the sulphurous gases in the vacuum retaining chamber are pumped back 90 from the pump D into the digester A through the pipes m n p and s. Whenever in the course of a digesting operation it is found necessary to introduce additional sulphurous gas into the digester, this is done by the 95 pump D which draws the gas either from the pipe M or from the recovery tank F through the pipe v and pumps it through pipes m n p and (preferably) r into the bottom of the digester. To change the liquor after any blowing off of the pulp the valve 10 is kept closed, and when all the pulp has been blown into and accumulated in the vacuum retaining chamber, valve 13 is closed and steam is admitted at 32 to fill the vacuum and generate 105 a steam pressure in the chamber B, whereupon the valve 35 is opened and the liquor is forced or runs out through the pipe u into the recovery tank. Fresh liquor is then supplied from the sulphite mixer through pipe o, 110 pump K, pipe p, cock 26 and pipe q. At the final blowing off of the pulp into the vacuum retaining chamber the spent liquor is drawn off in the same manner, and the sulphurous gas is then driven off from the pulp by admitting steam through valve 33, so that it ascends through the mass of pulp, while at the same time the valve 13 being opened the pump D is operated to draw off the sulphurous gas thus expelled. When the sulphurous gas has thus been sufficiently eliminated, 115 valves 13 and 33 are closed and valves 10 and 31 are opened, so that water enters the vacuum retaining chamber and the pulp is washed down into the pump L which forces it through 120 pipes h' and h³ into one of the wash-tanks G.

The agitator in the sulphite mixer E need be revolved only at the times when gas is being pumped into it by the pump D, or injected from the pipe M'.

Whenever during the digestion it is desired to draw off the sulphurous gas from the digester, this is done by closing the valve 13 and opening the valve 18 and operating the

6
pump D, so that the gas is drawn off through the pipe l. It may be pumped into the sulphite mixer and its place supplied by fresh gas, or it may be pumped back through the 5 pipes m n p and r into the digester.

If that part of my invention which has reference to the sulphite mixer E be not used, its functions may be performed in a measure by the usual lime tower, in which case instead of liquids and gases being pumped into the tank E, the liquids will be pumped to the top of the tower and the gases be pumped into its bottom, as is usual in the operation of such towers. The liquid drawn from the 10 bottom of the tower will be conducted to the pump K which will distribute it through the pipes p q r and s in the manner shown. The use of the sulphite mixer is preferred, however, on account of the greater cheapness and 15 expedition in the recovery of the sulphurous gas, and because the gas is confined so that it cannot escape to the atmosphere and give rise to foul odors.

It will of course be understood that equivalent devices or means may be substituted for the means shown. For example, the pumps I, J, K and L, instead of being centrifugal pumps may be any other kind or construction of pump, or any other apparatus known 20 to the arts which is capable of substitution for a pump to accomplish the same work. For example, a mante-jus may be substituted for the pump L; or in any case where a pump is used to transfer a liquid from one closed 25 vessel to another, the pump may be omitted entirely and the transfer be effected by establishing a difference of pressures between the two vessels, the one from which the liquid is being expelled being given an internal 30 pressure sufficiently greater than that in the vessel to which the liquid is being introduced, to overcome the friction and other resistance opposing the flow of the liquid; or the respective vessels may be arranged at different 35 levels so that the liquid will flow from the higher to the lower vessel upon the establishment of an equilibrium of internal pressures. The latter arrangement is shown in connection with the vessels B and F, the 40 former being shown arranged on a higher level than the latter, so that the liquid runs off itself whenever the valve 35 is open and the pressures in the two vessels are the same or nearly so. If the tank F, however, were 45 arranged on the same level as the chamber B, or at a higher level, it would be necessary to introduce a pump into the pipe u, as in the case of the pumps K and L.

All of the modifications of apparatus and 50 their connections together shown in my said Patents Nos. 369,834 and 369,836, in so far as the same are applicable in connection with my present invention, are to be construed as though their illustration and description 55 were repeated in my present application. For example, the substitution for the vacuum pump D as the means for maintaining the

vacuum in the vacuum retaining chamber, of an ejector, may be made and will serve some of the purposes of my present invention. 70

In my said application, Serial No. 327,615, of which the present application is a division, wherein is described the herein-described process of digesting and disrupting, there is claimed the process of preparing paper pulp 75 consisting in partially digesting the fibers, then disrupting the fibers by blowing them into the vacuum, and then resuming the digestion, and repeating the blowing into a vacuum until the fibers are reduced to the desired fineness. There is also therein claimed so much of the herein described apparatus as is necessary for carrying out the process claimed in said application; that is to say, there is claimed the digester, the vacuum 80 chamber, the vacuum pump, and the connections between the same which enable the fibers, solution and gases to be transferred back and forth between said digester and vacuum chamber. All of the matter claimed 85 in said application I herein disclaim.

I claim as my invention the several improvements in the disintegration of fibrous matter for the manufacture of paper-pulp and in apparatus therefor, defined as follows, 90 each substantially as hereinbefore specified, namely:

1. The combination of the digester, the vacuum retaining chamber connected therewith into which the contents of said digester are 100 discharged and retained, the vacuum pump connected on its suction side with the upper part of said vacuum retaining chamber, and a recovering conduit leading from the discharge side of said pump, substantially as 105 set forth, whereby the fibrous material when discharged from said digester into said vacuum retaining chamber is disrupted and retained in said chamber, and the disengaged gases are drawn off by said pump and discharged into said recovering conduit for further utilization. 110

2. The digester, the vacuum retaining chamber connected therewith into which the contents of said digester are discharged and 115 retained, the vacuum pump connected on its suction side with the upper part of said vacuum retaining chamber, and a recovering conduit leading from the discharge side of said pump, in combination with a spent liquid 120 draining pipe leading from the bottom of said vacuum retaining chamber, a valve therefor, a steam-introducing pipe opening into the bottom of said vacuum retaining chamber, and a valve therefor, substantially as set 125 forth, whereby the steam is forced through the drained pulp and the gases are drawn off therefrom by the vacuum pump while the pulp is within the vacuum retaining chamber.

3. The digester, the vacuum retaining 130 chamber connected therewith into which the contents of said digester are discharged and retained, the vacuum pump connected on its suction side with the upper part of said vac-

uum retaining chamber, and a recovering conduit leading from the discharge side of said pump, in combination with a spent liquid recovery tank, a pipe leading from the bottom 5 of said vacuum retaining chamber to said recovery tank, a valve in said pipe, means for heating the contents of said recovery tank, and a pipe leading from the upper part of said recovery tank to a vacuum pump, substantially as set forth, whereby the digesting 10

gas is recovered from the spent liquid drawn off from the vacuum retaining chamber.

In witness whereof I have hereunto signed my name in the presence of two subscribing witnesses.

HENRY BLACKMAN.
